UNITED STATES PATENT OFFICE.

SIDNEY A. KELLER, OF NEW YORK, N. Y., ASSIGNOR TO R. BLACKINTON & CO., OF NORTH ATTLEBORO, MASSACHUSETTS, A FIRM.

DESIGN FOR A HANDLE FOR SPOONS, FORKS, OR SIMILAR ARTICLES.

SPECIFICATION forming part of Design No. 36,292, dated April 21, 1903.

Application filed March 28, 1903. Serial No. 150,068. Term of patent 7 years.

To all whom it may concern:

Be it known that I, SIDNEY A. KELLER, a citizen of the United States, residing at New York, in the county of New York and State 5 of New York, have invented a new, original, and ornamental Design for the Handle of a Spoon, Fork, or Similar Article, of which the following is a specification, reference being had to the accompanying drawings, forming 10 part thereof.

Figure 1 is a view of the obverse side of the handle, showing my design. Fig. 2 is a view of the reverse side of the same.

The handle is shown as attached to the bowl 15 of a spoon in solid lines, the tined blade of a fork being indicated in broken lines.

As shown in the drawings, my design consists of the conventional fiddle-shaped handle having a pointed enlargement on the end of 20 the blade and on the obverse side an unbroken marginal bead inclosing a panel having the configuration of the handle. On the panel, at the lower part of the stem, is the raised

representation of leaves and fruit and on the blade a branch having leaves, buds, and 25 blossoms of the apple-tree arranged to bring the blossoms on the blade where it merges with the stem and in the pointed enlargement on the end of the blade. The reverse side of the handle has on the blade the raised 30 representation of three short branches of the apple-tree with leaves and buds.

Having described my invention, what I claim as new, and desire to secure by Letters Patent, is—

The ornamental design for the handle of a 35 spoon, fork, or similar article, as herein shown and described.

In testimony whereof I have signed my name to this specification in the presence of 40 two subscribing witnesses.

SIDNEY A. KELLER.
